DESIGN FOR A CASING FOR A COMBINED WASHING MACHINE AND DRIER

Walter D. Teague, Forest Hills, N. Y., assignor to
Nineteen Hundred Corporation, Binghamton,
N. Y., a corporation of New York

Application September 18, 1934, Serial No. 53,319

Term of patent 14 years

To all whom it may concern:

Be it known that I, Walter D. Teague, a citizen of the United States, residing at Forest Hills, in the county of Queens and State of New York, have invented a new, original, and ornamental Design for a Casing for a Combined Washing Machine and Drier, of which the following is a specification, reference being had to the accompanying drawing, forming a part hereof, in which:

The drawing is a perspective view of a casing for a combined washing machine and drier.

The appearance of the machine as viewed from

the opposite side will be the same as indicated in the drawing with the exception of the relation of the drain-board to the main casing and the omission of the depression and control handle at the center of the casing. The opposite side, therefore, will present a continuous, unbroken surface similar to that forming the major part of the view shown.

I claim:

The ornamental design for a casing for a combined washing machine and drier, as shown and described.

WALTER D. TEAGUE.
